UNITED STATES PATENT OFFICE.

FREDERICK LAIRD, OF CLAYPOOL, OKLAHOMA.

DISK-PLOW ATTACHMENT.

1,286,354.

Specification of Letters Patent.

Patented Dec. 3, 1918.

Application filed July 20, 1918. Serial No. 245,901.

To all whom it may concern:

Be it known that I, FREDERICK LAIRD, a citizen of the United States, residing at Claypool, in the county of Jefferson and State of 5 Oklahoma, have invented certain new and useful Improvements in Disk-Plow Attachments, of which the following is a specification, reference being had to the accompanying drawings.

10 This invention relates to certain improvements in disk plow attachments and it is an object of the invention to provide a novel and improved device of this general character which can be readily and conveniently 15 applied to the standard or sheth of a shovel cultivator.

It is also an object of the invention to provide a novel and improved attachment of this general character wherein the disk comprised therein may be readily and conveniently adjusted as the occasions of practice may require together with means to maintain the disk in its required position.

The invention consists in the details of 25 construction and in the combination and arrangement of the several parts of my improved disk plow attachment, whereby certain important advantages are attained and the device rendered simpler, less expensive 30 and otherwise more convenient and advantageous for use, as will be hereinafter more fully set forth.

The novel features of my invention will hereinafter be definitely claimed.

35 In order that my invention may be the better understood I will now proceed to describe the same with reference to the accompanying drawings, wherein:

Figure 1 is a view partly in front elevation 40 and partly in section illustrating a disk plow attachment constructed in accordance with an embodiment of my invention and in applied position, the coacting portion of a cultivator standard or sheth being shown in 45 fragment.

Fig. 2 is a view in side elevation of my improved attachment as herein disclosed, and

Fig. 3 is a view in top plan of the plate comprised in my attachment as herein em- 50 bodied.

As disclosed in the accompanying drawings P denotes a plate preferably of metal and which is substantially rectangular in form and provided along one longitudinal 55 edge with a slot 1 through which the bolts

2 or the like are adapted to be directed for clamping the plate to the standard or sheth of a shovel cultivator after the shovel or plow has been removed.

The opposite longitudinal portion of the 60 plate P has integrally formed therewith a barrel or sleeve 3 open at its opposite ends and through which is directed the shaft 4.

The shaft 4 is of a length to extend through the barrel or sleeve 3 beyond the opposite 65 ends thereof. Embracing or surrounding the upper end of the shaft 4 is a sleeve 5 carried by an end portion of an arm or lever 6. The sleeve 5 is held to the upper end portion of the shaft 4 through the medium of 70 the clamping screw 7 threaded through said sleeve and having binding contact with the shaft 4. By this means the arm or lever 6 may be readily removed when the occasions of practice may so require. The upper end 75 portion of the plate P is provided with a laterally directed web 8 having its marginal portion provided with the depending teeth or rack 9 with which coacts the pivoted latch 10 carried by the outer end portion of the 80 arm or lever 6. The working end of the latch 10 is constantly urged toward the teeth or rack 9 to effect the desired locking engagement therewith through the medium of the expansible member 11 herein disclosed 85 as a conventional coil spring interposed between the arm or lever 6 and the tail portion 10^a of the latch 10.

The lower end portion of the shaft 4 is provided with the laterally directed and sub- 90 substantially perpendicularly related extension or spindle 12 which serves as a mounting for the disk plow D.

H denotes a tubular hub closed at its outer end and which is adapted to be loosely 95 mounted upon the spindle 12 and said hub substantially midway its length is provided with an outstanding annular flange 14 to which the disk plow D is detachably secured through the medium of the removable 100 bolts 15.

The inner or open end portion of the hub H is also provided with an outstanding annular flange 16 and engageable therewith is the sand cap 17 carried by the inner end 105 portion of the spindle 12. The sand cap 17 serves to hold the hub H in applied position upon the spindle 12 yet permits said hub H to be readily removed when the requirements of practice necessitate.

The plate P provides means whereby my improved attachment may be readily and conveniently applied to the standard or shaft of a shovel cultivator or the like and the arm or lever 6 permits the disk D to be adjusted into the position desired while the latch 10 coacts with the teeth or rack 9 for holding the disk in its required position. It will therefore be self evident that my improved attachment can be employed to conveniently convert a shovel cultivator into a rotary disk cultivator.

From the foregoing description, it is thought to be obvious that a disk plow attachment constructed in accordance with my invention is particularly well adapted for use by reason of the convenience and facility with which it may be assembled and operated and it will also be obvious that my invention is susceptible of some change and modification without departing from the principles and spirit thereof and for this reason I do not wish to be understood as limiting myself to the precise arrangement and formation of the several parts herein

shown in carrying out my invention in practice except as hereinafter claimed.

I claim:

A disk plow attachment comprising an elongated plate provided with a longitudinally disposed slot whereby the plate may be adjustably secured to a support, a longitudinal margin of said plate being provided with a barrel, a shaft disposed through the barrel and provided at one end portion with a spindle, a lever engaged with the opposite end portion of the shaft, a laterally directed web carried by the end portion of the plate adjacent the lever, said web being provided with downwardly directed teeth, and a latch underlying and carried by the lever and movable in a direction longitudinal of the barrel and engageable with the teeth of the web.

In testimony whereof I hereunto affix my signature in the presence of two witnesses.

FREDERICK LAIRD.

Witnesses:

J. M. HENDERSON,
F. O. LAIRD.
